(57) **CLAIM**

We claim the ornamental design for the adjustable light, as shown and described.

DESCRIPTION

FIG. 1 is a front perspective view showing the adjustable light in its environment;

FIG. 2 is a perspective view looking from the left, rear side of the light;

FIG. 3 is a perspective view looking from the right, rear side of the light;

FIG. 4 is left-side view;

FIG. 5 is a right-side view;

FIG. 6 is a rear view;

FIG. 7 is a front view;

FIG. 8 is a top view; and,

FIG. 9 is a bottom view.

The broken lines shown on the drawings are for illustrative purposes only and form no part of the claimed design.
